APPARATUS FOR THE STRINGING OF
TENNIS RACKETS

James Hutton Proctor, Northbridge, near Sydney, New South Wales, Australia, assignor to Ace Racket Stringers (Worlds Rights) Limited, Sydney, New South Wales, Australia, a company of New South Wales

Application June 22, 1932, Serial No. 618,746
In Australia July 10, 1931

5 Claims. (Cl. 273—73)

This invention consists in apparatus for stringing tennis rackets.

In the practice of the trade the longitudinal string is first drawn through the holes in the racket frame starting from the central strings and working outwards, the frame is then struttured longitudinally to prevent distortion and the string lengths are then separately tautened up and tensioned successively; as each length is drawn taut by the workman it is checked by pushing an awl wedge into the outgoing hole in the frame so as to jamb it, and it is then "twanged", the sonorous note emitted being the indicator relied on by the workman for ascertaining the degree of tension.

After the "mains" or longitudinal strings are thus tensioned and secured, the "cross" strings are similarly drawn through the appropriate holes in the frame, and like the longitudinal strings are then tautened, tensioned, and secured.

Continuous strings for the longitudinal courses and for the transverse courses are used in my stringing method which follows conventional practice insofar as the insertion and awling of strings is concerned; each separate string length in the lattice being separately tensioned. Change in the tension strings due to the stretching of any particular string course is checked by frictional resistance where the strings are reeved through the holes in the frame.

According to the present invention, the racket frame is cramped up to symmetrical shape on an open centre flat oval ring carrier by means of demountable screw cramps which bear against the outer periphery of the bow. The racket frame is thus held firmly during the stringing operation and distortion of the frame shape is prevented. Any one of the screw cramps is removable during the stringing operation where it is found necessary to obtain access to a frame hole which happens to be so located that it is obstructed by it; when any cramp is thus removed it is replaced temporarily by a like cramp in a close-by position, thereby to maintain the symmetrical shape of the racket frame as the stringing proceeds. The cramps are also adjustable to suit rackets differing in contour, from one another. For factory operation the ring carrier is detachably fixed on a turntable to enable the operator to reverse the frame end-for-end or side-for-side as the stringing proceeds, thus to relieve him of the necessity for moving his position, to obviate loss of time, and generally to facilitate the manipulations.

In the drawing:

Fig. 1 is a plan view of a racket frame cramped on a carrier ring, with its handle cramped on an extension arm on which the ring is supported;

Fig. 2 is a plan view of a turntable fixed on a workbench with a pedal pull line for operating the tensioning tool;

Fig. 3 is a side elevation showing a ring frame with a racket thereon set up on the turntable (Fig. 2) and a pedal line connected to the tensioning tool;

Fig. 4 is a perspective view of one of the screw pad cramps and

Fig. 5 is a fragmentary section explanatory of the mounting of the turntable on a ring bed.

The oval ring carrier frame 10 is fixed to the bench arm 11 by screws 12, the arm 11 being clamped or bolted to a fixed table, a bench, or a post. Holes 13 are drilled down through the ring 10 to receive the dowel studs 14 of the cramps (Fig. 4). Each cramp is provided with a screw 15 which is tapped through the cramp headpiece 16 from which the studs 14 depend; its point bears against the downturned end 17 of the saddle pad 18 which is loosely located by its downturned tailpiece 19 through which the stem of the cramp screw 15 passes. These cramps are set up on the ring 10 and on the bench arm 11 as seen in Fig. 1, and their screws are operated to cramp the racket frame 20 to true shape and to set it symmetrically with the racket handle. The peripheral part of the frame and the interior part of it are accessible to the workman. Where any one of the cramps happens to obstruct one of the string holes another cramp is set up in a close-by position and the obstructing cramp is removed whilst the string is being manipulated in the hole, access to which it had prevented.

When required to be used on a turntable (Fig. 2) the carrier ring 10 is fixed to ring 22 by means of screws 21. Ring 22 is fitted with lugs 52 through which check screws 50 are passed to engage a peripheral groove 51 in the turntable ring 22^A and a ball race is provided to facilitate rotation of ring 22 on turntable 22^A. To fix the ring 10 in relation to the base ring 22^A one of the screws 50 may be replaced by a wing screw.

An outrigger 24 with the bearer piece 24^A forms a convenient turntable base. It is screwed down (25) to a support 26. When the tensioning tool is required to be pedal operated, a lever 27 is fulcrumed at 28 on the outrigger 24, and a flexible line 29 is carried from the bottom end of the lever 27 over a pulley 40 to a pedal (not shown). The top end of the lever is provided with a

shackle or other attachment for pulling on the back end of the tensioning tool 30.

As each course of string is tensioned it is checked temporarily at the outgoing frame hole by means of a wedge-awl and the next course of the string is then drawn taut and tensioned and similarly checked, and so on for all the longitudinal and transverse string courses successively until the frame is fully strung.

10 The tensioning tool 30 seen in Fig. 3 is the subject of my copending application Serial No. 717,854, filed March 28th, 1934.

Instead of the back check against which the butt end of the racket handle bears, a check 15 engaging the concave face of the fore end of the racket bow may be provided on the carrier frame 10.

What I claim as my invention and desire to secure by Letters Patent is:—

20 1. Apparatus for stringing tennis rackets, comprising an open centre carrier frame, an extension arm on said carrier frame for supporting the handle of a racket the bow of which is set on the carrier frame, a check for locating the racket endwise on said frame and arm, a clamp for holding the handle centrally on the extension arm, a plurality of screw cramps having stems which are adapted to set into holes in the carrier frame, said cramps exercising inward pressure about the racket bow to adjust its set and shape.

25 2. Apparatus for stringing tennis rackets, comprising an open centre carrier frame, having holes about its periphery, a fixed sub-frame on which said carrier is rotatably mounted, an extension arm on said carrier frame for supporting the shaft of a racket the bow of which is set on the carrier frame, a check for locating the racket endwise on said frame and arm, and a plurality of screw cramps having socket stems which seat 30 into said holes in the carrier frame, said cramps

exercising inward pressure on the racket bow to adjust its set and shape.

3. Apparatus for stringing tennis rackets comprising an open centre carrier frame having holes about its periphery and having an extension arm, a circular sub-frame adapted to be mounted on a fixture, a ball race supporting the carrier frame on the sub-frame, said sub-frame having a peripheral groove therein, guide fingers on the carrier frame movable in said groove to position the carrier frame rotatably on the sub-frame, a check for positioning the racket endwise on said frame and arm, and a plurality of screw cramps having stems which seat into said holes in the carrier frame, said cramps exercising inward pressure about the racket bow to adjust its set and shape.

4. Apparatus for stringing tennis rackets, comprising an open center carrier frame having holes therin, an extension arm on said carrier frame for supporting the handle of a racket the bow of which is set on the carrier frame, a check for positioning the racket endwise on said frame and arm, a clamp for holding the handle centrally on the extension arm, a plurality of demountable screw cramps having stems which seat into said holes in the carrier frame, said cramps exercising inward pressure on the racket bow to adjust its set and shape.

5. Apparatus of the kind described for stringing tennis rackets, comprising a carrier frame having holes about its periphery, and a plurality of screw cramps having stems which seat into said holes, said cramps being adapted to locate a racket on said carrier frame and to exercise inward pressure about the bow of the racket to adjust its set and shape, each of said cramps being demountable and fixable in another position to facilitate access to the stringing holes without releasing the bow.
